MEANS TO FLARE TUBE ENDS AND TO
PREVENT THEIR RUPTURE

William L. Linker, Warwick, and James R. Welshman, Cranston, R. I., assignors to Grinnell Corporation, Providence, R. I., a corporation of Delaware

Application January 29, 1946, Serial No. 644,110

5 Claims. (Cl. 153—79)

1

This invention relates to improvements in means to flare tube ends and to prevent their rupture. More especially it has to do with flaring the end of tubing which has a longitudinal weakness such that it is likely to open up during the flaring operation.

It is an object of our invention to provide means which prevent rupture of the tubing while it is being flared and which can readily be discarded when the flaring is complete.

The best mode in which we have contemplated applying the principles of our invention is shown in the accompanying drawings but these are merely illustrative for it is intended that the patent shall cover by suitable expression in the claims whatever features of patentable novelty exist in the invention disclosed.

In the drawings:

Fig. 1 is an exploded view of the flaring tool, the resisting washer and a section of tubing;

Fig. 2 is an elevation partly in medial longitudinal section, showing the elements arranged for the flaring to begin;

Fig. 3 is a similar view, showing the changes in relations of the elements during the flaring operation; and

Fig. 4 is another similar view, showing the completion of the flaring.

Referring to the drawings, and particularly to Fig. 1, the tubing 10 to be flared is one having a longitudinal weakness, such as a seam which results from making the tubing from flat sheet material. The edges of such a sheet are usually beveled and so disposed opposite one another in the finished tubing that the all-around thickness will be uniform. While the seam thus formed is tight enough to withstand the internal pressure to which the tubing may be subjected, it is not sufficiently strong to permit the end of the tube being flared by an ordinary tool 12 such as is shown in the drawings.

This tool comprises a cylindrical shank 12a adapted to fit within the tubing, a cone-shaped portion 12b constituting the flaring surface and a head 12c which receives blows or a pressure that forces the shank and flaring surface within the tubing 10. A shoulder 12d is provided at the larger end of the flaring surface. If such a tool is driven into tubing having a weak longitudinal seam, the latter almost invariably opens up. In short, it is practically impossible to flare such tubing in the usual way.

Our invention resides in providing a resisting washer 14 which is made of strong but yieldable metal in the form of a dished ring. The diam-

eter of the hole in this ring approximates that of the shank 12a or the smaller end of the cone-shaped portion 12b of the flaring tool and from the edge 14a of this hole the ring 14b diverges at a suitable angle, say about 45°, from the axis of the washer.

The dished washer, as shown in Fig. 2, is laid on the top edge 10a of the tubing to be flared, and the shank 12a of the flaring tool is passed through the washer 14 and into the tubing until the edge 14a of the washer makes contact with the flaring surface 12b. The tubing is now held by any suitable means (not shown) and the flaring tool forced further into the tubing. This may be done by repeated blows of a hammer or by pressure imposed by a press.

As the tool advances into the tubing the edge 10a is gradually expanded and the wall of the tubing is gradually flared as at 10b. Simultaneously the washer 14 is deformed in that its top edge 14a is made larger and its ring 14b assumes a lesser degree of divergence from the axis of the washer. (See Fig. 3.) During these changes in the tubing and washer the latter tightly engages the top edge of the tubing with resisting effect and prevents any opening up of the seam.

At the very end of the flaring operation the edge 10a of the tubing, is forced to the end of the flaring surface 12b, and the edge 14a of the washer is expanded so that both edges rest against the shoulder 12d of the flaring tool. The latter can now be withdrawn and the washer removed, leaving a perfectly flared end on the tubing with the seam as strong as before the flare was made.

35 We claim:

1. Means for flaring tubing having a longitudinal seam, comprising a flaring tool having a shank fitting within the tubing, having a flaring surface to form the flare on the tubing and having a head adapted to be acted upon to force the flaring surface within the tubing; and a dished-shaped washer having a hole corresponding in size to that of the shank of the flaring tool and having a ring disposed outwardly at an angle to the axis of the washer; the washer being initially placed on the shank of the flaring tool with the inner edge of its ring resting on the edge of the tubing and acting thereafter while the tubing is flared to maintain a resisting force on the tubing to prevent opening-up of the said longitudinal seam; said washer being expanded simultaneously with the flaring of the tubing so as to be removable upon the completion of the flaring operation.
2. Means for flaring tubing comprising a dished-shaped washer having a hole with a di-

ameter approximating the inner diameter of the tubing to be flared and having a ring disposed at an angle to the axis of the washer, and a tool having a flaring surface whose smaller end has a diameter approximating that of the hole in the washer; said washer being placed on the edge of the tubing with its ring diverging beside the tubing and being expanded by said flaring surface while maintaining a resisting effect on the tubing to prevent rupture thereof as said surface is forced into the tubing; said washer being removable from the tubing upon the completion of the flaring operation.

3. Means for flaring tubing comprising a flaring tool having a tapered surface adapted to be forced into the tubing to effect the flaring thereof, and a dished-shaped washer having the diameter of its inner edge approximating the diameter of the smaller end of said surface; said washer being placed on the edge of said tubing with the said inner edge of the washer adjacent the flaring surface and with the ring of the washer extending beside the tubing so that as the flared surface of the tool is forced into the tubing the washer maintains a resisting force on the tubing to prevent rupture of the tubing as the flaring thereof takes place; said washer being expanded simultaneously with the flaring of the tubing so as to be removable upon the completion of the flaring operation.

4. Means for flaring tubing comprising a dished-shaped washer having its inner edge of a diameter approximating that of the inner diameter of the tubing to be flared and having a ring diverging from said inner edge; and a flaring tool having a diameter at its smaller end approximating that of the inner diameter of the tubing and having a shoulder outstanding from the larger end of the flaring surface; the washer being placed on the edge of the tubing with its ring extending beside the tubing so that as the

flared surface is forced into the tubing the ring maintains a resisting force on the tubing to prevent rupture thereof during the flaring operation; the edge of the tubing and the inner edge of the washer being both in contact with the said shoulder at the termination of the flaring operation; and the washer being removable from the tubing at the completion of the flaring operation.

5. Means for flaring tubing comprising a flaring tool having a tapered surface adapted to be forced into the tubing to flare the end thereof; and a dished-shaped washer having the diameter of the inner edge of its ring approximating the diameter of the smaller end of said tapered surface and having the diameter of the outer edge of its ring greater than the diameter of the larger end of said tapered surface; the washer being placed on the edge of the tubing with its ring diverging beside the tubing and being expanded while maintaining a resisting force on the tubing as the flared surface is forced into the tubing; the ring continuing to be divergent in shape so that upon completion of the flaring operation the washer can be slipped off the edge of the flared tubing.
